LOCK

Henry G. Voight, Hamden, Conn., and Samuel Oxhandler, Flushing, N. Y., assignors to Sargent & Company, New Haven, Conn., a corporation of Connecticut

Application August 6, 1945, Serial No. 609,182

4 Claims. (Cl. 70—144)

1

This invention relates to locks, and more particularly to a lock system so designed that a number of different locks may be made from many of the same identical parts. Moreover, the mechanical features of the lock proper are so designed that the lock structure, including the case in which it is mounted, may be employed for either a mortise lock set into a mortise in the door or what is termed a unit lock, which lock is completely assembled before being mounted and then mounted in an opening cut through the edge of the door.

In Patent No. 2,304,612, issued to Henry G. Voight, on December 8, 1942, there is shown a lock system wherein the same basic parts may be employed for making a number of different locks, depending upon the use to which the desired lock is to be put. The simplest of the lock structures, of course, requires the fewest parts, and the more complicated structures are made by using those parts employed in the simplest lock and adding additional parts. In the present application, the same general principle is employed, but has been extended so that the resulting lock may, principally by choice of the proper escutcheon plates, be either a mortise lock or a unit lock. That is to say, according to the teaching of the present invention, some six or eight different types of locks may be made, and any of these may be either a mortise lock or unit lock as desired.

One object of the present invention is to provide a lock structure from the parts of which a number of different locks may be made.

Still another object of the invention is to provide a lock structure having lock mechanism and a supporting case so arranged that the mechanism and case may be employed either in connection with a mortise lock or a so-called unit lock.

A still further object of the invention is to provide a lock having escutcheon plates and bolt-operating means, such as knobs, rotatably mounted in the escutcheon plates, the latter being so connected to the lock case that perfect alignment of the knobs with the retracting mechanism inside the case will be assured.

To these and other ends the invention consists in the novel features and combinations of parts to be hereinafter described and claimed.

In the accompanying drawings:

Fig. 1 is a front elevational view of a mortise lock embodying my invention mounted upon a door;

Fig. 2 is an elevational view of the lock shown in Fig. 1 looking at the edge of the door;

Fig. 3 is a sectional view on line 3—3 of Fig. 1;

Fig. 4 is an elevational view of the inner face of the escutcheon plate and associated knob structure;

Fig. 5 is a view of the lock case with the cover removed showing the interior mechanism;

Fig. 6 is a fragmentary sectional view on line 6—6 of Fig. 5;

Fig. 7 is a view similar to Fig. 6, but showing the lock with a straight face instead of a beveled face as shown in Fig. 6;

Fig. 8 is a view similar to Fig. 1 showing my invention as applied to a unit-type lock;

Fig. 9 is an elevational view of the lock shown in Fig. 8 looking at the edge of the door;

Fig. 10 is a sectional view on line 10—10 of Fig. 8;

Fig. 11 is a sectional view on line 11—11 of Fig. 8;

Fig. 12 is an inside elevational view of the escutcheon plate and associated parts;

Fig. 13 is a sectional view on line 13—13 of Fig. 12; and

Fig. 14 is a front elevational view of the lock case with the face plate removed and with the outer escutcheon secured thereto.

As illustrated in Fig. 1 of the drawings, I have shown a lock comprising a case 10 adapted to be set in a mortise in the door 11. The case 10 comprises a rear plate or base member 12, and a cover plate 13, these plates standing opposite each other, and the base or inner plate 12 being provided with posts 14 having threaded sockets to receive screws passed through the cover plate to secure these two parts of the case together.

The case also comprises a front plate 15 which, as shown in Figs. 6 and 7, may be secured to the front and rear walls of the case, so that a lock with either a beveled face or straight face may be provided.

In order to secure the face plate 15 to the case, an attaching plate 16 provided with four lugs 17 is secured to the plate 12 by having one of the lugs 17 passed through an opening in the plate 12 and then staked over to secure it in place. Another of the lugs 17 is passed through an opening 18 in the face plate 15 and staked over, thus securing the face plate 15 to the plate 12.

It will be understood that a similar plate 16 is provided at both top and bottom of the plate 12, and it will also be noted that, while one of the front and lower edges of the plate 17 is cut off and extends at right angles to the plate 12, the other edge extends at an angle to this plate. Therefore, when securing the plate 16 to the plate 12, it may be secured in either one of two reversed positions, so that the forward edge of the plate 16 may present either a straight face or an inclined surface, depending upon whether or not a lock with a beveled face is desired.

It will be understood that the plate 16 is secured to the plate 12 prior to screwing the cover plate 13 thereto, and the latter is provided with an opening to receive another of the lugs 17, so that the front and rear plates and also the face plate 15 will be rigidly secured together. In Fig. 6 of the drawings a lock with a beveled face is illustrated, while in Fig. 7 of the drawings the plate 16 has been reversed end-for-end,

and the straight face thereof projects forwardly, thus providing a lock with a straight face.

A finishing plate 19 may be secured to the plate 15 by screws 20, this finishing plate concealing the openings 18 in which the lugs 17 are staked and being only provided with the proper openings to permit the projection therethrough of the parts of the lock which is being made. Thus, in the present lock, the face plate 19 is provided only with openings for the bolt and 10 the dogging means, as will be hereinafter described, aside, of course, from the openings for the screws 20. The rear of the lock case and the top and bottom thereof between the plates 12 and 13 may be closed by a U-shaped sheet metal member 21 which acts only, however, as a cover or shield and plays no part in securing the other parts of the case together.

As shown in Fig. 5, the present lock is provided with a latch bolt 22 adapted to project from the front of the case, this bolt being actuated by a yoke or retractor 23 and urged to protracted position by a spring 24 acting against the bolt head and against a post 24 secured to the plate 12 of the case. Rotatably mounted within the case are three rollback hubs 25, 26 and 27, each of which is independently rotatable and each of which carries arms engageable with laterally turned ends 28 at the rear of the yoke 23, so as to move the yoke when any one of the rollbacks is rotated. The hubs 25 and 27 are carried by sleeves 29 and 30 secured to the front and rear walls of the case, while the intermediate rollback 26 is rotatably carried by the rollbacks 25 and 27. As this particular arrangement of the rollbacks is well-known in the art, further description thereof is believed to be unnecessary.

The particular type of lock shown in Figs. 1 to 5 is usually called a vestibule lock which is provided only with a latch bolt and dogging mechanism to dog the latch bolt from operation by the outside knob, and key-operated means are provided in the outside knob to operate the bolt when the latter is dogged. The dogging mechanism may be of any of the usual types but, as herein shown, comprises a slide 32 operated from the face of the door by stop buttons 33, the slide being provided with a pin 34 adapted to enter an opening 35 in the outer rollback hub and thus dog this hub against movement.

The inner knob 36 is secured to a knob shank 37, this shank being provided with a tenon 38 upon its end designed to be received in a slot 39 of the inner rollback 25, so that the latter will be operated by rotation of the knob. It will also be noted that the knob shank is rotatably mounted in a sleeve 40 secured to the inner escutcheon plate 41, so that the knob is supported by and rotatably mounted on this plate. Spacing sleeves 42 are also secured to this plate, these sleeves being secured in place by a plate 43 disposed adjacent the escutcheon plate 41 and secured thereto by the staking over of the inner end of the sleeve 40 as shown at 44.

The plate 43 is provided with offset portions 45 to overlie the heads of the sleeves 42 to secure the latter to the escutcheon plate. The knob shank 37 may be held against movement by a split washer 46 received in a recess 47 in the shank and in engagement with the inner end of the sleeve 40. It will be apparent from this construction the knob is rotatably mounted in the escutcheon plate and that the sleeves or hollow posts 42 are also secured to the escutcheon plate and extend inwardly to be received in lo-

cated openings in the lock case as will be herein-after more fully described.

The outer knob 50 is secured to a hollow shank 51 rotatably mounted in a sleeve 52, and sleeves or hollow posts 53 similar to the post 42 are secured to the outside escutcheon 54 by the plate 55, the inner end of the sleeve 52 being staked over this plate. The hollow shank 51 is secured in place by the split washer 56, so that, with the exception of the fact that the knob shank is hollow, the construction of the outer escutcheon and knob assembly is substantially the same as that described in connection with the inside. Also, the knob shank is provided with a tenon 57 which is engaged in a recess or slot in the outer rollback 27.

Mounted in the outside knob is the usual key-operated lock 59 having a key barrel 60 to the inner end of which is secured a spindle 61 extending loosely through the hollow shank 51 and non-rotatably engaged with the intermediate rollback hub 26, so that operation of the key barrel by the key will result in the retraction of the bolt when the outside rollback is dogged.

The walls of the lock case 12 and 13 are provided with registering openings 63 and 64 (Fig. 5), which openings are adapted to receive the reduced ends of the sleeves 42 and 53 when the parts of the lock are assembled. In the mounting of the lock upon a door, the lock case with its enclosed mechanism is inserted in a mortise made through the edge of the door. The inner and outer knob and escutcheon plate assemblies are then put into place, the sleeves 42 and 53 extending into the openings 63 and 64 as shown in Fig. 3, which locates the escutcheon plates, knob shanks, and the spindle 61 accurately with respect to the rollbacks 25, 26, and 27. Screws 65 are inserted through the sleeves 42 and threaded into the sleeves 53, so that the escutcheons will be firmly secured to the lock case and to the door. If the thickness of the door varies, it is only necessary to vary the lengths of the sleeves 42 and 53 and the screws 65.

It will thus be seen that while the knobs are carried by the escutcheon plates, the knob shanks are accurately positioned by means of engagement of the sleeves 42 and 53 with the lock case, so that there will be no binding of the parts and that there will be a perfect alignment of the rollback hubs on the one hand of the knob shanks and lock spindle on the other hand. Moreover, the fact that the knobs are carried by the escutcheon plates assures that the knobs will always stand at the same distance from the door, regardless of the thickness of the door which is not the case where the knobs are carried by the lock case itself.

In Figs. 8 to 14 of the drawings, I have shown my invention as applied to a unit lock. The parts of this lock are, in the main, exactly similar to the parts already described, but changes are made in certain elements, owing to the fact that in a unit lock the escutcheon plates are secured directly to the lock case, so that the lock may be applied as a unit instead of in two or more parts as is the case with mortise locks. The lock case itself and the mechanism therein is the same as that previously described except that, as shown in Fig. 14, the front plate 70 is somewhat shorter than the plate 15 being substantially the same length as the height of the lock case itself. Likewise, the face plate or finish plate 71 is of the same length as the plate 10, but is provided with rearwardly directed flanges 72 and 73, so that the

escutcheon plates 74 and 75 may overlap these flanges.

The inner and outer knobs 76 and 77 are assembled with the escutcheon plates as are the knobs 36 and 50, and the knob shank and spindle construction is like that previously described. Also retaining plates 78 and 79 are provided, the retaining plate 79 securing the sleeves 80 and 81 to the inside escutcheon, while the retaining plate 78 secures sleeves 82 and 83 to the outside escutcheon, which sleeves are adapted to enter the openings 63 and 64 and locate the escutcheon relatively to the lock case.

Also, additional sleeves 84 and 85 are secured to the outside escutcheon by the retaining plate 78, these sleeves being adapted to receive screws 86 (only one of which is shown, Fig. 10) to secure the outside escutcheon to the case. It will be apparent that the escutcheon 74 is, therefore, firmly secured to the lock case, but that slight play is allowed between the inner escutcheon plate 75 and the lock case by the sleeves 80 and 81 to provide for any slight inequalities in the thickness of the door and to enable the escutcheons to be drawn up tightly to the door by the screws 87 and 88 passing through the sleeves 80, 81, 82 and 83.

It will, of course, be understood that the screws 86 are put into position prior to the assembly in the lock mechanism in the case in the making of the unit lock. Likewise, the inside escutcheon 75 is provided with openings for screws 89 (Fig. 10) to screw into the door to hold the lock in place.

In the usual and well-known manner of assembling a unit lock, the parts of the lock, including the escutcheon plate, are all assembled with the lock case and then placed in an opening in the door. With the present lock, it is only necessary then to tighten the screws 87 and 88 and insert the screws 89 to mount the lock in place. Moreover, it will be seen that the same lock mechanism together with the case, with the exception of the front plate, is used in making both the mortise and the unit lock shown in the present application, and that in each case the escutcheons which carry the knobs are accurately located with respect to the case by sleeves secured to the escutcheons and received in openings in the walls of the case. By the use of the same parts for both types of locks, cost of manufacture is greatly reduced, and when to this is added the fact that with the same case and with the use of the same mechanism for the most part, many different types of locks may be made for uses upon doors in various locations, a great saving in expense in manufacture is effected. Moreover, by reversing the plates 16, either a straight face or a beveled face lock may be provided. In each case, the front face of the lock will be selected according to the openings desired in the face. That is, where both a dead bolt and a latch bolt are provided, for example, a face plate will be selected having openings for both bolts, whereas, in the present application, only one opening is provided, as the lock is provided with a latch bolt only.

While I have shown and described some preferred embodiments of my invention, it will be understood that it is not to be limited to all of the details shown, but is capable of modification and variation within the spirit of the invention and within the scope of the claims.

What we claim is:

1. A door lock comprising a case having

10 mounted therein a bolt and bolt-retracting mechanism, escutcheon plates at each side of the case, knobs rotatably mounted in said escutcheon plates and having shank portions entering the case and there operatively engaging said retracting mechanism, means securing said escutcheon plates to the case in definite relation thereto to insure proper alignment of the knobs with the retracting mechanism, said means comprising sleeves secured to the escutcheon plates, said case having openings to receive said sleeves, a face plate secured to the case, said face plate having rearwardly directed flanges, and the forward edges of said escutcheon plates overlapping the rear edges of said flanges.

15 2. A door lock comprising a case having mounted therein a bolt and bolt-retracting mechanism, escutcheon plates at each side of the case, knobs rotatably mounted in said escutcheon plates and having shank portions entering the case and there operatively engaging said retracting mechanism, means securing said escutcheon plates to the case in definite relation thereto to insure proper alignment of the knobs with the 20 retracting mechanism, said means comprising sleeves secured to the escutcheon plates, said case having openings to receive said sleeves, and screws passing through the sleeves at one plate and secured to those of the other plate.

25 3. A door lock comprising a case having mounted therein a bolt and bolt-retracting mechanism, escutcheon plates at each side of the case, knobs rotatably mounted in said escutcheon plates and having shank portions entering the case and there operatively engaging said retracting mechanism, sleeves secured to said escutcheon plates, the inner ends of which enter openings in the case, means securing said escutcheon plates to the case, plate members embracing said 30 sleeves, and means securing said members to the escutcheon plates to secure the sleeves to the escutcheon plates.

35 4. A door lock comprising a case having mounted therein a bolt and bolt-retracting mechanism, escutcheon plates at each side of the case, bearing sleeves secured to said escutcheon plates, knobs having shank portions rotatably mounted in said bearing sleeves, said shank portions extending into the case and there engaged with said retracting mechanism, means securing said escutcheon plates to said case to align the knob shanks with the retracting mechanism, said means comprising sleeve members received in openings in the case, plate members embracing the sleeve members, and said plate members being secured to the escutcheon plates by said bearing sleeves to secure the sleeve members rigidly to the escutcheon plates.
